UNITED STATES PATENT OFFICE.

PETER J. MURPHY, OF NEW YORK, N. Y.

WINDOW PORTAL.

Application filed May 21, 1926. Serial No. 110,727.

This invention relates to window portals and may constitute a portion of an automobile windshield, a side window of an automobile, a portion of a ticket selling booth, or 5 it may be used for many other purposes where it is desirable to have a movable portal or window.

A further object is to provide a device of this character which may be inserted in an 10 opening formed in a pane of glass, or in an opening in any other suitable material, and which requires no nails, screws, bolts or other securing means but is so constructed as to maintain itself in position when once 15 forced into engagement with the walls of an opening.

A further object is to provide a device of this character which may be manufactured and sold at a reasonably low price, which 20 will be ornamental and attractive in appearance, and which will be of great utility.

With these and other objects in view, the invention consists in certain novel features of construction and combinations and arrangements of parts which will be more fully hereinafter described and pointed out in the claim.

In the accompanying drawings—

Figure 1 is a view in elevation, taken from 30 the inside or inner face of the window and portal;

Figure 2 is an enlarged fragmentary view in elevation, showing the portal open;

Figure 3 is a fragmentary perspective 35 view, showing the portal holding ring in position on a pane of glass;

Figure 4 is a perspective view of the complete ring;

Figure 5 is an enlarged view in section, 40 on the line 5—5 of Figure 1.

1 represents a pane of glass which may constitute, as above stated, a windshield, a window at the side of an automobile or a portion of a ticket selling booth. In this 45 window I provide a circular opening 2 for the reception of my improved device, which constitutes two main parts, namely, a ring 3 and a portal 4. The portal 4 may constitute the piece of glass which has been cut 50 from the window 1, slightly reduced in diameter, or it may be a separate part permanently connected to the ring 3 and sold as an entirety.

The ring 3 is of rubber or other analogous 55 material having in its outer face an annular groove 8 to receive the edge of the glass 1

and firmly grip the same. This groove may be of any desired depth but it is of course to be understood that the material employed must be such as to enable the ring to be 60 manipulated and engage the glass 1 with such firmness and fixity as to make the joint weathertight and securely couple the parts together.

The portal 4, as above explained, preferably 65 constitutes a piece of glass or other transparent material and fits within the ring 3, the latter being provided with an annular flange 5 which limits the inward movement of the portal and insures a perfectly 70 tight joint between the portal and the ring when the portal is closed.

The portal and the ring are connected by my improved hinge construction, illustrated 75 most clearly in Figures 1, 2 and 5. This hinge construction comprises two leaves 6 and 7. The leaf 6 is secured to the ring 3, preferably by rivets 8 and 9, and is located within a recess 10 in the ring 3 so as to preferably lie flush with the inner face of the 80 ring. This leaf 6 has a sleeve 11 fixed thereon intermediate of its ends and at its forward edge.

The other leaf 7 which is secured to the portal 4, preferably by rivets 12, has a pair 85 of sleeves 13 and 14 spaced apart and located in alignment with the sleeve 11 and connected thereto by a hinge pin 15. The sleeve 13, which is above the sleeve 11, is formed with a bevel tooth 16 which is adapted to ride 90 over the upper end 17 of sleeve 11 and fall behind a shoulder 18 on said sleeve when the portal is opened so as to prevent accidental return or closing movement of the portal.

A spring 19 connects the two leaves of the hinge and tends to move the portal to closed position. This spring may constitute a coil located around the hinge pin 15 between the sleeves 11 and 14, with one end 20 of the spring 19 secured under the leaf 6 while the other end 21 of spring 19 is projected through an eye 22 on the leaf 7.

The operation of the portal is as follows: When it is desired to open the portal it is 105 simply necessary to exert sufficient pressure on the same to force it outward until it reaches a position where the tooth 16 will fall behind the shoulder 18 and thus hold the portal in open position. When it is desired 110 to close the portal it is necessary to elevate the same sufficiently to disengage the tooth

16 from the shoulder 18, when the spring 19 will return the portal to its closed position.

I would call particular attention to the fact that I provide slits 22' which are located 5 in a rubber ring above and below the hinge so as to provide a tongue or lip 21' which is bendable but which is always in position in front of the spring and hinge parts so as to protect the spring and the hinge from the 10 weather.

While I have illustrated what I believe to be a preferred embodiment of my invention it is obvious that various slight changes and alterations might be made in the general 15 form of the parts described without departing from the invention and hence I do not limit myself to the precise details set forth

but consider myself at liberty to make such slight changes and alterations as fairly fall within the spirit and scope of the appended 20 claim.

I claim:

A device of the character described, comprising a grooved flexible ring adapted to engage the wall of an opening, said ring having an internal annular flange at one edge, a portal, a spring hinge, one leaf of which is secured to the ring and the other to the portal, with the pintle of the hinge and the spring located adjacent one edge of the 25 portal and in a recess of the ring, and a flexible tongue on the ring extending across said recess and over a portion of the portal. 30

PETER J. MURPHY.
